WALKIE-TALKIE

Hiroharu Shimazaki, Tokyo, Japan, assignor to Kanda
Tsushin Kogyo Kabushiki Kaisha, Tokyo, Japan

Filed June 9, 1965, Ser. No. 85,644

Term of patent 14 years

(Cl. D26—14)

FIG. 3.

FIG. 4.

FIG. 5.

FIG. 1 is a bottom front and side perspective view of a walkie-talkie, showing the design of the invention;

FIG. 2 is a top, front and left-side perspective view thereof;

FIG. 3 is a rear elevational view thereof;

FIG. 4 is a right-side elevational view thereof;

FIG. 5 is a fragmentary left-side elevational view thereof, and

FIG. 6 is a fragmentary left-side perspective view, to an enlarged scale, showing the control push-button in greater detail.

The characteristic features of the new design reside in the combination on a walkie-talkie of an edgewise projecting square frame having slightly outwardly curved sides and enclosing a recessed inverted pyramid-shaped and perforated microphone-speaker grille, and of a rectangular

control push-button on the side of the walkie-talkie with a dished-in outer surface having substantially the same configuration as the grille, all as shown.

I claim:

The ornamental design for a walkie-talkie, substantially as shown and described.
